UNITED STATES PATENT OFFICE.

GEORGE A. NEWMAN, OF ST. PAUL, MINNESOTA.

DEVICE FOR DECORATING WALLS AND SIMILAR SURFACES.

Application filed December 13, 1926. Serial No. 154,441.

My invention relates to devices for decorating walls and similar surfaces. An object of the invention is to provide a device by means of which walls and similar surfaces 5 may be decorated much more expeditiously and conveniently than by the customary method of stenciling patterns thereon. The device embodied in the present invention is in the nature of an improvement on the device 10 disclosed in my patent No. 1,607,295 dated November 16, 1926, in the use of which device paint is applied to a pattern in relief carried by a base member and the pattern is pressed while the paint thereon is still wet, upon suc- 15 cessive portions of the wall, additional paint being supplied from time to time as required to impart the proper amount of paint to the wall. In the device of the present application, a pattern in relief is produced by means 20 of finely divided pieces of absorbent material secured to the base member by an adhesive. In this manner on account of the absorbent material, the number of times it is necessary to recharge the pattern with paint is reduced 25 to a minimum.

The full objects and advantages of my invention will appear in connection with the detailed description thereof, and the novel features of my inventive idea will be particu- 30 larly pointed out in the claim.

In the accompanying drawings which illustrate my invention in two slightly different forms,—

Fig. 1 is a face view of the device. Fig. 2 35 is a view in section on the line 2—2 of Fig. 1. Fig. 3 is a view similar to Fig. 2 but showing a slight modification.

Referring to the drawings, the numeral 10 40 designates a base member consisting of flexi- ble sheet material which may be translucent

paper. A pattern in relief designated by the numeral 12 is produced on one side of the base member by means of absorbent material secured thereto by an adhesive such as glue. The absorbent material preferably consists of 45 finely divided pieces of sponge. In the form shown in Fig. 3, the base member consists of a block 10' to which the pattern 12 is secured in the manner stated.

The operation and advantages of my invention will now be obvious. On account of 50 the employment of finely divided pieces of absorbent material for producing the raised pattern, it is comparatively easy to outline the pattern and secure the absorbent material 55 within the outlines of the pattern by means of an adhesive. In the use of the device, paint of the desired color is applied to the pattern which is then pressed upon successive portions of the surface which is to be decorated. Additional paint is applied to the absorbent material constituting the pattern from time to time as necessary to impart the 60 proper amount of paint. On account of the absorbent nature of the pattern, the device 65 can be used for a much longer time without replenishing the paint than would otherwise be the case.

I claim:

A device for decorating walls comprising 70 a flat base member having a pattern outlined thereon and finely divided pieces of sponge secured by an adhesive to said base member, said pieces of sponge filling the space within the limits of said outlined pattern to produce 75 a pattern in relief.

In testimony whereof I hereunto affix my signature.

GEORGE A. NEWMAN.
